UNITED STATES PATENT OFFICE.

WILLIAM F. TUBESING, OF MILWAUKEE, WISCONSIN.

REINFORCED CONCRETE STRUCTURE.

1,127,702.

Specification of Letters Patent.

Patented Feb. 9, 1915.

Application filed August 21, 1908. Serial No. 449,605.

To all whom it may concern:

Be it known that I, WILLIAM F. TUBESING, a citizen of the United States, residing at Milwaukee, in the county of Milwaukee and State of Wisconsin, have invented certain new and useful Improvements in Reinforced Concrete Structures, of which the following is a specification, reference being had to the accompanying drawing, forming a part thereof.

The main objects of this invention are to simplify, strengthen and improve structures of this class; to facilitate their erection, to produce substantially flat ceilings, to so arrange the metal reinforcing bars or rods in floors and ceilings as to take any reversal of moment and with the reinforcing bars or rods in the lower parts of the beams to afford the wind bracing required in high buildings; to avoid the necessity of bending the reinforcing bars or rods except those of small size or section which can be readily bent as they are placed in the structure; and to admit of the employment in the form work of such standard dimensions of lumber as will not be easily broken in handling and may therefore be used over and over again indefinitely.

It consists in certain novel features of construction and in the peculiar arrangement and combinations of parts as herein-after particularly described and pointed out in the claims.

In the accompanying drawing like characters designate the same parts in the several figures.

Figure 1 is a plan view of a panel illustrating the arrangement of the metal reinforcing members before the concrete is applied thereto, the structure for the four adjoining panel corners and the supporting column being shown as complete in the lower right hand part of the figure; Fig. 2 is a vertical cross section through the panel on the line 2-2, Fig. 1, showing a part of the form work in place and the concrete as applied to the reinforcing structure; Fig. 3 is an isolated view of one of the tie bars forming a part of the reinforcing structure; and Fig. 4 is a similar view of one of the bars surrounding the columns and resting on the umbrella-like structures for supporting the superposed metal work in the upper part of the slabs at the corners of the panels.

At the upper ends of the supporting columns and the corners of the horizontal

panels or slabs carried thereby, the structure resembles that of an umbrella, the ends of the umbrella ribs at the four corners of each panel with the sides of the beams defining a substantially circular middle section, which may be regarded as a circular plate or slab, while the umbrella-like structures at the corners, of which the columns represent the umbrella handles, may be regarded as cantilevers, the beams being assumed to take the load not directly carried by the umbrellas.

Referring to the drawing, the steel or metal bars and rods, which may be of the usual commercial forms and constitute the reinforcing structure, are arranged as follows: *a* designates vertical column bars extending continuously from the columns through the horizontal floor and ceiling slabs and beams, as shown in Fig. 2, each column being provided with four or more of these bars, which are held in place at intervals by hoops or ties *b*, as shown at the left in Fig. 2. Tie rods *c*, one of which is shown by itself in Fig. 3, running lengthwise through the upper part of the beams, span the sides of the panels and are bent around the outer or farther column bars *a*, as shown in Fig. 1, the ends of the rods extending obliquely back into the panel which they bound and representing the ribs of the umbrella-like structures at the corners of the panels, one of such structures being shown complete in the lower left hand part of Fig. 1. These rods being of comparatively small section or size, are readily bent as they are placed in position, and serve when the structure is complete, to bind the column members of the entire structure together. Toward the ends where they are bent around the bars *a*, they are brought to the upper part of the panels or horizontal slabs supported by the columns and their obliquely bent ends radiating from the columns are inclined downward so as to take the moment produced in the cantilevers, as indicated by dotted lines in Fig. 2. On the ends of the tie rods *c*, radiating from the several columns into the corners of the adjoining panels, are placed supporting rods *d*, one of which is shown by itself in Fig. 4, to afford bearings for and carry reinforcing rods spanning the panels diagonally and parallel with the beams in the upper part of the slabs adjacent to the corners of the panels, as hereinafter explained. These support-

ing bars are bent as shown, to the form of a square or otherwise, so as to surround the columns at a distance therefrom, one or more being placed around each column, and 5 they are bent inwardly and lapped at the ends where they are brought together. Across the tie rods *c* on two opposite sides of each panel, and across the rods *d* adjacent to their ends, are then laid at suitable 10 intervals, parallel with the tie rods *c* on the other two sides of the panel, reinforcing rods *e*. In like manner, across the rods *e* are laid at corresponding intervals, reinforcing rods *f*, and then upon the rods *e* and 15 *f* are laid two sets of diagonal rods *g* and *h*, the several rods *e*, *f*, *g* and *h* spanning the several panels and being brought adjacent to the corners of the panels into the upper part of the concrete floor and ceiling slabs, 20 where they are supported by the rods *d* resting on the tie rods *c* and their inwardly and obliquely bent ends in position, to take the reversal of moment to which the umbrella-like cantaliver structures at the corners of 25 the panels are subjected. These rods *e*, *f*, *g* and *h*, are lapped when necessary, where they cross the tie rods *c* in or adjacent to the beams spanning the spaces between the columns. Rods *i*, running lengthwise 30 through the lower part of the beams inside of the vertical column bars *a* and below the tie rods *c* serve to strengthen the beams and in connection with the tie rods afford the wind bracing required in high buildings.

35 The form work, which may consist mainly of lumber of such standard dimensions as will not be easily broken in handling, and may consequently be used again and again indefinitely, is built up as shown in Fig. 2, 40 to produce molds for the columns and beams and a support for the panel slabs carried by the columns and beams. As shown, 2-inch planks *j*, laid at suitable intervals on 4x4 inch stringers *k*, carry a floor *l* of boards or 45 of plain or corrugated sheet metal, on which the horizontal panel slabs of the concrete structure are molded and supported till the concrete has set or hardened sufficiently to permit the removal of the form work. The 50 stringers *k* are supported at intervals by short 4x4 inch cross pieces *m*, resting on vertical 4x4 inch struts or posts *n* and braced therefrom by diagonal strips *o*. The beams are made of such a depth that lumber 55 of standard dimensions, as for example, 4x4 inch pieces *p*, may be used to form the sides which project below the ceiling or lower surface of the intervening panel slabs. These pieces are beveled on the sides next to 60 the beams, so that they may be readily removed without disturbing the concrete, and they are supported on 2-inch planks *q*, which form the bottoms of the molds for the beams. The planks *q* are supported at 65 intervals, like the stringers *k*, on short 4x4

inch cross pieces *m*, carried by vertical struts or posts *n*, from which they are braced in like manner by diagonal strips of wood *o*.

In Fig. 2, *r* designates the columns, *s* the 70 beams and *t* the floor and ceiling slabs, the form work being removed from the column at the right.

After the metal reinforcing structure has been arranged and the form work has been 75 erected as above explained, the concrete is molded in the usual manner around the metal structure, and when it has set or hardened sufficiently to admit of it, the form work is removed in condition for further 80 use in the erection of similar structures.

I claim:

1. A reinforcing framework for a monolithic concrete column-supported floor slab structure comprising vertical reinforcing 85 bars for the columns, tie rods in the slab connecting the reinforcing bars of adjacent columns and bent around said reinforcing bars and extending back obliquely to themselves into the floor slab, the obliquely bent 90 ends of said rods radiating in different directions from each column, and an enveloping monolithic concrete mass for the framework.

2. A reinforcing framework for a monolithic concrete column-supported floor slab structure, comprising vertical reinforcing bars passing continuously upward through the columns and the slab, tie rods connecting the reinforcing bars of adjacent 100 columns, spanning the slab adjacent to the sides thereof and bent around said bars and back obliquely to themselves into the slab in which their obliquely bent ends radiate in different directions, and an enveloping 105 monolithic concrete mass for the framework.

3. A reinforced monolithic concrete structure comprising slabs carried at the corners by columns, and a reinforcing framework 110 comprising vertical column reinforcing bars, and tie rods connecting reinforcing bars of adjacent columns, spanning the slabs adjacent to the sides thereof and bent around the farther bars of said columns and back obliquely to themselves into the slabs, the ends of certain rods radiating in different directions from each column and forming an umbrella-like structure.

4. A reinforced monolithic concrete structure comprising slabs carried at the corners by columns and beams spanning the spaces between the columns and projecting a short distance below the intervening slabs; and a reinforcing metal frame work comprising 120 vertical column reinforcing bars passing continuously through the columns and the slabs at the intersections of the beams, tie rods running lengthwise through the upper part of the beams and bent around the col- 125 130

- umn bars and back obliquely to themselves into the slabs, in which their obliquely bent ends radiate in different directions from the columns, said rods connecting reinforcing 5 bars of adjacent columns, and reinforcing rods running longitudinally through the lower part of the beams below the tie rods.
5. A reinforced monolithic concrete structure comprising slabs carried by columns 10 and beams spanning the spaces between the columns; a reinforcing metal framework comprising vertical column-reinforcing bars, tie rods running lengthwise through the beams and bent in the upper part of the 15 slabs around said bars and back obliquely to themselves into the slabs, in which their obliquely bent ends radiate in different directions from the columns, said rods connecting reinforcing bars of adjacent columns, and reinforcing rods embedded at intervals in each slab and extending across the tie rods into the adjoining slabs.
6. A reinforced monolithic concrete structure comprising columns, beams carried by 25 the columns and spanning the spaces between them and slabs bridging the spaces between the beams; and a reinforcing metal framework comprising vertical column reinforcing bars, tie rods running lengthwise 30 through the beams and bent around said bars and back obliquely to themselves into the slabs, in which their obliquely bent ends radiate in different directions from the columns, said rods connecting reinforcing bars of adjacent columns, reinforcing rods passing through the slabs at intervals parallel with the beams and across the tie rods, and reinforcing rods passing obliquely through the slabs across the other reinforcing rods. 35
7. A reinforced concrete structure comprising slabs, beams carried by the columns and spanning the spaces between them, slabs bridging the spaces between the beams, vertical reinforcing bars in the columns, tie rods running lengthwise of the beams and 40 bent around the outer column bars in the upper part of the slabs, the ends of said rods extending obliquely back into the slabs which they bound, supporting rods resting on said tie rods around the column bars, and 45 reinforcing rods running through the slabs and resting on said tie rods and supporting rods substantially as described.
- In witness whereof I hereto affix my signature in presence of two witnesses.
